SHEET CLAMPING MEANS FOR PRINTING DEVICE

Wilson W. Perry, Box 625, Falls Church, Va.
Filed Aug. 15, 1961, Ser. No. 131,528
6 Claims. (Cl. 101—415.1)

This invention relates to improvements in printing or duplicating devices and particularly to sheet clamping means for rolls of printing and duplicating machines.

It is a principal object of the invention to provide improved clamping means for printing and duplicating machine rolls which is simple in construction, positive in operation and relatively inexpensive to manufacture thereby obtaining maximum efficiency with a minimum of expense and maintenance.

Another object of the present invention is to provide a clamping device for rolls of a printing or duplicating machine that may be advantageously employed on master cylinders and/or blanket rolls of offset printing devices.

A further object of the present invention is to provide such a device that is readily adaptable to be received on substantially any grooved plate or blanket receiving roll of duplicating machines and is readily adjusted to accommodate various thicknesses of master sheets and/or blankets.

A further object of the present invention is to provide such a clamping device wherein an entire end of a master sheet or blanket is securely and snugly clamped to its cooperating roll substantially eliminating torn master sheets and blankets often occurring with clamping devices engaging only portions of ends of master sheets and blankets.

A further object is to provide an improved clamping device for rolls of duplicating machines wherein centrifugal force and/or friction between cooperating rolls which would normally tend to urge master sheets and blankets out of clamping engagement with their respective rolls increases the frictional engagement between the clamping device and the material being clamped on the respective rolls.

These and other objects and advantages of the present invention are provided in a printing device including a master and a blanket roll having grooves extending longitudinally across the cylindrical surfaces thereof, an impression roll operatively aligned with the master and blanket rolls and means for directing ink to the outer surface of the master roll, the combinations consisting of means for securing a web or sheet of material to said master and blanket rolls comprising a bar, said bar having cylindrical end portions and between said cylindrical end portions said bar being generally quadrangular in transverse cross section, a pair of bearing blocks adapted to receive the cylindrical end portions of said bar, means mounting one of said pair of bearing blocks in the grooves of said rolls adjacent each end of the groove to position a planar face of said bar in parallel spaced relation to the trailing edge of the grooves in said respective rolls, and handle means secured to said bar for pivoting said bar about the bearing blocks to a sheet receiving and removing position and to a position wherein a radially inner edge of said planar face of the bar urges an end of the sheet into clamping engagement with said trailing edge of the roll grooves.

Other objects and advantages of the present invention will be apparent to those skilled in the art from the following detailed description of the present invention when considered in light of the accompanying drawings wherein:

FIG. 1 is a diagrammatic sectional view of a conventional offset type duplicating machine having rolls provided with the novel clamping means of the invention;

2

FIG. 2 is an enlarged fragmentary perspective view of one of the rolls of the device shown in FIG. 1 illustrating in detail the improved clamping means of the invention;

FIG. 3 is a section substantially on line 3—3 of FIG. 2;

FIG. 4 is a fragmentary end view of the clamping device of the present invention with a web clamped between the clamping bar and the trailing surface of a roll groove; and

FIG. 5 is a fragmentary perspective view of a modified form of the invention wherein the bearing blocks for the clamping device adjustably carry sheet stop means.

Referring to the drawings and, in particular, to FIG. 1 thereof, 10 generally designates a duplicating machine 15 employing the improved clamping means of the present invention and comprises an impression roll or cylinder 12, a blanket cylinder or roll 14 having a blanket 16 about the generally cylindrical surface thereof. The blanket roll 14 is provided with a groove 18 in the cylindrical surface thereof with the improved clamping means 20 of the invention mounted adjacent the trailing edge 22 of the groove 18.

The assembly also includes a cylinder roll 24 having mounted thereon a master sheet or plate 26. The plate roll or cylinder 24 is provided with a groove 28 formed in the cylindrical surface thereof, which groove is similar in construction to the groove 18 of roll 14.

The groove 28 of roll 24 is provided with the improved clamping device of the present invention generally 30 designated 20' for maintaining the master sheet or plate 26 on said roll. The clamping device 20' is mounted adjacent the trailing edge 30 of the groove 28.

The duplicating machine also includes suitable water applying means generally designated 32 and including a water fountain 34, a fountain roll 36, a ducor roll 38, a metal oscillator 40 and a form roller 42, all as commonly known in the art. The duplicating machine 10 further includes an inking system 44 comprising an ink fountain 46, a fountain roll 48, a ducor roll 50, a distributor roll 52, an oscillator roll 54, ink forming roll sets 56 and 58, and a further oscillator roll 60.

In operation of the duplicating device illustrated in FIG. 1, a master sheet or plate with indicia thereon is provided with ink and water from the ink and water systems 32 and 44 which ink is transferred to the blanket 16 securely secured to the blanket roll or cylinder 14 and the transferred ink is then deposited on a sheet of paper as the paper passes through the nip between the blanket roll and the impression roll or cylinder 12. A substantial pressure is required between the various ink and water applying rolls, contacting the roll surface of the plate cylinder 24 and a relatively high pressure is maintained at the nip between the blanket roll 14 and the master sheet carrying roll 24. In view of these substantial pressures, it is necessary to securely clamp the leading ends of the master sheet and the blanket to the trailing edges of the grooves provided in the plate cylinder and blanket cylinder to immobilize the master sheet and blanket sheet during operation of the duplicating device.

Referring to FIGS. 2, 3 and 4 of the drawings, details of the improved clamping device as applied to the plate cylinder or roll 24 is illustrated in detail, with like structures being provided with identical reference characters employed in describing the structures in FIG. 1.

In FIG. 2, the master sheet roll 24 is illustrated as being of the type wherein the groove 28 extends across the cylindrical surface 64 completely on end 66 while it terminates short of the opposite end 68. However, it will be appreciated by those skilled in the art that the groove 28 may extend to both ends 66 and 68 or may terminate short of both ends without departing from the scope of the present invention.

The groove 28 has a leading edge 70 and a trailing edge 30. Adjacent the trailing edge are mounted a pair of bearing blocks 72 and 72'. Each of the bearing blocks 72 and 72' is provided with an elongated slot 74 extending centrally therethrough which elongated slots are adapted to receive fastening means such as bolts 76 which threadedly engage the bottom surface 78 of the groove 28 securing each of the bearing blocks in its predetermined position.

Further, the bearing blocks are bored as at 80 to receive cylindrical ends 82 of the clamping bar 29, whereupon the bar may be rotated about the axis of the cylindrical ends 82. Between these cylindrical ends 82, the clamping bar may be quadrangular in cross section as more clearly illustrated in FIG. 3. However, it is necessary that the bar have one quadrangular face 84 and a cooperating lower edge in order to insure simple insertion and removal of the sheet and positive clamping of the sheet to the roll. One of the quadrangular faces 84 is mounted in spaced parallel relationship to the trailing edge 30 of the groove 28 with the spacing between the face 84 and the surface 30 of the groove 28 being so selected that the leading edge of the particular master sheet may be freely inserted between the face 84 and the face 30 when the face 84 is generally in a plane parallel to the face 30 of the groove 28.

The clamping assembly also includes a manual actuating lever 86 illustrated as a cylindrical bar, one end of which is securely received in a cooperating bore in face 88 of the clamping rod 62. It will be noted that the face 88 is the face parallel to the face 84 previously described.

The extended end 90 of the manual actuating bar 86 may be bored to receive end 92 of a tension spring 94 while the opposite end 96 of the spring is secured by bolt means 98 to the base of the groove 28 in the roll whereby the handle 86 and the clamping bar 62 are urged by the spring 94 into a clamping position. The urging of the spring aids in preventing the handle from pivoting upwardly during high-speed actuation of the duplicating machine.

Referring again to FIG. 3 of the drawings, the handle 86 is manually urged in the direction of the directional arrow 100 when the leading end of the master sheet is being inserted or removed from between face 84 of the clamping bar 62 and face 30 of the groove 28. With the master sheet in position, the handle is released and the spring 94 urges the handle in the opposite direction to the directional arrow 100 which urges edge 102 of the bar 62 into contact with the outer surface of the master sheet 26 which, in turn, urges the inner face of the master sheet into engagement with the trailing edge 30 of the groove 28 securely clamping the master sheet on the master roll. As illustrated, edge 102 may be slightly rounded to prevent the clamping force of the edge from cutting the master sheet during clamping thereof.

It will be particularly noted that any force tending to urge the leading edge of the master sheet 26 from its clamped position will increase the clamping force provided by the edge 102 of the bar 62, thus insuring positive anchoring of the leading edge of said sheet 26.

While the foregoing invention has been primarily described with reference to the master sheet roll of a duplicating machine as hereinbefore discussed, a similar clamp may advantageously be employed to secure the blanket 16 to the blanket roll 14 as illustrated at 20 in FIG. 1 of the drawings.

Further, in the illustrated forms of the invention, a single clamping device is employed adjacent the trailing edge of the respective grooves of the master and blanket rolls whereby the trailing ends of the blanket and the master sheet are unconnected to their respective rolls. Where desired, a similar clamping device may be employed adjacent the leading edges of the respective grooves of said rolls whereby the trailing edge of the attached master sheets and blankets may also be anchored.

Referring to FIG. 5 of the drawings, there is shown a modified form of the present invention wherein the bearing blocks for the rod are provided with stop means for the sheet to be clamped to the roll. In FIG. 5, each of the bearing blocks 72' has adjustably secured thereto member 110 having a foot portion or stop member 112. In the illustrated form of the invention, member 110 is slotted as at 116 and limited vertical movement of the member relative to its bearing block is provided by loosening the clamping screws 118.

Where desired, cooperating indicia may be provided on the member 110 and the bearing block as shown at 114 to permit accurate relative adjustment of the pair of members 110.

Through the use of the stop members 110, the operator may simply and accurately place master sheets on the master roll in serial succession. Further, with the improved stop member, a master sheet may be canted a predetermined amount by placing one stop member at a different height relative to its companion stop member.

From the foregoing description of the present invention, it will be appreciated that various modifications may be made in the form of the improved clamping device without departing from the spirit of the present invention as defined in the following claims.

I claim:

1. In a printing device including a roll having a groove extending longitudinally across the cylindrical surface thereof and means cooperating with a wall of said groove for clamping a sheet to the cylindrical surface of the roll comprising a bar, said bar having at least one rectangular face and a cooperating clamping edge, said clamping edge being continuous and substantially coextensive with the wall of the groove, cylindrical end portions for said bar, a pair of bearing blocks adapted to receive the cylindrical end portions of said bar, means mounting one of said pair of bearing blocks in the groove of the roll adjacent each end of the groove to position said one face of said bar in parallel spaced relation to the trailing edge of the groove, and handle means secured to said bar for pivoting said bar about the bearing blocks to a sheet receiving and removing position and a position wherein a clamping edge of the said one face of the bar secures an end of the sheet in clamping engagement with said trailing edge of the roll groove, and a stop member adjustably carried by each of said bearing blocks.

2. In a printing device including a roll having a groove extending longitudinally across the cylindrical surface thereof and means cooperating with a wall of said groove for clamping a sheet to the cylindrical surface of the roll comprising a bar, said bar having cylindrical end portions and between said cylindrical end portions said bar being generally quadrangular in transverse cross section, a pair of bearing blocks adapted to receive the cylindrical end portions of said bar, means mounting one of said pair of bearing blocks in the groove of the roll adjacent each end of the groove to position a planar face of said bar in parallel spaced relation to the trailing edge of the groove, handle means secured to said bar for pivoting said bar about the bearing blocks to a sheet receiving and removing position and a position wherein a radial inner edge of the said planar face of the bar secures an end of the sheet in clamping engagement with said trailing edge of the roll groove and resilient means connected to said roll and said handle means for urging said radial inner edge of said bar into clamping engagement with said end of the sheet, said radial inner edge being continuous and substantially coextensive with the trailing edge of the roll groove.

3. In a printing device including a master roll having a groove extending longitudinally across the cylindrical surface thereof, an impression roll operatively aligned with the master roll and means for directing ink to the outer surface of the master roll; the combination con-

sisting of means for securing a master sheet to said master roll comprising a bar, said bar having cylindrical end portions and between said cylindrical end portions said bar being generally quadrangular in transverse cross section, a pair of bearing blocks adapted to receive the cylindrical end portions of said bar, means mounting one of said pair of bearing blocks in the groove of the master roll adjacent each end of the groove to position a planar face of said bar in parallel spaced relation to the trailing edge of the groove, handle means secured to said bar for pivoting said bar about the bearing blocks to a master sheet receiving and removing position and a position wherein a radial inner edge of said planar face of the bar urges an end of the master sheet into clamping engagement with said trailing edge of the master roll groove, and resilient means normally urging said handle means and said bar to a position wherein said radial inner edge is in contact with said master sheet, said radial inner edge being continuous and substantially coextensive with the trailing edge of the roll groove.

4. In a printing device including a master roll, an impression roll operatively aligned with the master roll and having a groove extending longitudinally across the cylindrical surface thereof, means for directing ink to the outer surface of the master roll; the combination consisting of means for securing a blanket sheet to said blanket roll comprising a bar, said bar having cylindrical end portions and between said cylindrical end portions said bar being generally quadrangular in transverse cross section, a pair of bearing blocks adapted to receive the cylindrical end portions of said bar, means mounting one of said pair of bearing blocks in the groove of the blanket roll adjacent each end of the groove to position a planar face of said bar in parallel spaced relation to the trailing edge of the groove, handle means secured to said bar for pivoting said bar about the bearing blocks to a blanket sheet receiving and removing position and a position wherein a radially inner edge of said planar face of the bar urges an end of the blanket sheet into clamping engagement with said trailing edge of the roll groove, said radial inner edge being continuous and substantially coextensive with the trailing edge of the roll groove, and resilient means normally urging said radial inner edge of said bar into engagement with the blanket sheet.

5. In a printing device including a master roll, a blanket roll, and an impression roll, all operatively aligned, a groove extending longitudinally across the cylindrical surface of said master roll and said blanket roll, the combination consisting of means for securing a sheet to said master roll and to said blanket roll comprising a bar, said bar having cylindrical end portions and between said cylindrical end portions said bar being generally quadrangular in transverse cross section, bearing blocks

adapted to receive the cylindrical end portions of said bar, means mounting one of said bearing blocks to the groove of the master roll and the blanket roll adjacent each end of said groove to position a planar face of said bar in parallel spaced relationship to the trailing edge of each of said grooves, handle means secured to each of said bars for pivoting said bars about the bearing blocks to a sheet receiving and removing position and a position wherein a radial inner edge of said planar face of each of said bars urges an end of said sheet into clamping engagement with the trailing edges of each of said roll grooves, and resilient means normally urging the radial inner edge of each of said bars into clamping engagement with their respective sheets, the said radial inner edge of each of said bars being continuous and substantially coextensive with the respective trailing edges of each of said roll grooves.

6. In a printing device including a roll having a groove extending longitudinally across the cylindrical surface thereof and means cooperating with a wall of said groove for clamping a sheet to the cylindrical surface of the roll comprising a bar, said bar having cylindrical end portions and between said cylindrical end portions said bar having a planar face, said planar face defining at least one longitudinal edge therealong, said longitudinal edge being radially spaced from said cylindrical surface, a pair of bearing blocks adapted to receive the cylindrical end portions of said bar, means mounting one of said pair of bearing blocks in the groove of the roll adjacent each end of the groove to position said planar face of said bar in parallel spaced relation to the trailing edge of the groove, handle means secured to said bar for pivoting said bar about the bearing blocks to a sheet receiving and removing position and a position wherein said longitudinal edge of the said planar face of the bar secures an end of the sheet in clamping engagement with said trailing edge of the roll groove with the longitudinal edge making line contact with the end of the sheet, the planar face being out of parallelism with the trailing edge of the groove when the line contact is made and resilient means connected to said roll and said handle means for urging said longitudinal edge of said bar into clamping engagement with said end of the sheet, said longitudinal edge being continuous and substantially coextensive with the trailing edge of the roll groove.
